DIAL FOR RADIO APPARATUS

Erwin König, Berlin-Neukoelln, Germany, assignor to Allgemeine Elektricitäts Gesellschaft, Berlin, Germany, a corporation of Germany

Application October 22, 1935, Serial No. 46,111
In Germany November 7, 1934

4 Claims. (Cl. 116—124.3)

This invention relates to a dial for radio apparatus which affords a rapid and simple setting of the tuning means to a desired station.

Dials are already known in which the individual station names classified in wave lengths are divided into groups, while for selecting the desired group of transmitters a separate list such as a station alphabet is employed. These dials have the disadvantage that they lack considerably in clearness. The great number of station names listed in accordance with the frequency or wave-length brings confusion, renders difficult the selection and the setting to a definite station while not excluding the possibility of errors.

In accordance with this invention the total number of the station names is subdivided into groups. The individual groups are so arranged on the dial that always only one group appears in a window at which place it is suitably illuminated by direct light or through transparency. The dial which carries the station names is so mechanically connected with the tuning means that the latter are automatically set to a desired group of transmitters, when the names of this group appear in the window, so that only a fine adjustment is required in order to receive immediately a definite transmitter of the group through the loudspeaker. The arrangement is such that the individual groups are designated by letters so that they can be selected in the manner of the automatic phone dial when making a call. Within each group the station names are identified by means of a reference number.

The setting to a definite transmitter on the dial is done in such manner that the identification letter and identification number are determined from the station list, whereafter for instance by turning a knob the tuning means and the dial disk are set to the letter thereby obtaining directly the corresponding sub group and then the setting to the identification number of said station is carried out by means of a fine or vernier adjustment element. This setting is very simple and rapid and excludes any errors. The station name is read within each group by means of a single indicator especially assigned thereto such as, for instance, a graduation curve traced on a disk which is connected with the tuning means.

In accordance with a further feature of the invention, the arrangement is such that a loose mechanical coupling is provided between the said two setting or control devices. This may be accomplished for instance in that the setting device for the identification number is connected

with a disk or a band carrying the graduation curves or indicators for the individual transmitters, whereas the individual groups of transmitters are listed on another disk or on another band. If the graduation curve of one group has been moved past all station names, the tuning control of the indicator disk, due to the loose mechanical coupling, moves therewith the part having the groups of transmitters, for example by means of special cams or notches in the indicator disk, thus obtaining automatically a more rapid setting of the tuning means than would be possible by a simple rotation of the setting control.

For a better understanding of the invention, reference is made to the accompanying drawing in which:

Fig. 1 is a perspective view of a portion of the front panel of a radio receiver embodying the invention;

Fig. 2 is a perspective view showing the control and indicating device of Fig. 1 with the panel removed and,

Fig. 3 is a front view of the vernier control disk of Fig. 2, and Fig. 4 is a vertical sectional view taken through the line 4—4 of Fig. 1 but omitting the panel and tuning condenser.

Referring to the drawing, numeral 1 is a disk or indicator carrying the graduation curves 10 for the several transmitting stations and is rigidly secured to the tuning condenser shaft 13. On the disk 2 in front thereof, the station names are symmetrically listed in groups, the disk 2 and its attached gear wheel 5a being loosely mounted for free rotation on condenser shaft 13. As seen from Fig. 1 of the drawing, there appears of these station names in the window 11 formed in a plate 3 always only one group, while all remaining groups remain concealed behind plate 3 and its supporting panel 12. At the right and the left of this window the names of all stations which can be received by the receiver are alphabetically listed on a plate 3 secured to main panel 12. The two manual control knobs are designated by 6 and 7. The variable tuning condenser having a rotor shaft 13 is designated by 8. The handle 1 is fastened on the one hand to the rotor shaft 13 of variable condenser 8, and on the other hand, to the disk 1. The gear 5a is fixedly secured to the disk 2 both these members being loosely mounted for free rotation on shaft 13, while the gear 5b serves only for the transmission and rotates freely on a shaft 14. Gear 5c is rigidly connected with the switching wheel 4 and serves to rotate gear 5a and its 55

50 members being loosely mounted for free rotation on shaft 13, while the gear 5b serves only for the transmission and rotates freely on a shaft 14. Gear 5c is rigidly connected with the switching wheel 4 and serves to rotate gear 5a and its 55

attached disk 2 through the idler gear 5b, gear 5c and its attached wheel 4 being loosely mounted for free rotation on shaft 17 carrying the control knob 6. Disk 1 is driven by the knob 5 and a friction wheel 5d secured to the shaft 17 and contacting disk 1. The disk 1 is provided with a plurality of spaced lugs 16', as shown in Figs. 3 and 4. The lugs 16' are provided in the periphery of disk 1 by cutting a notch 16 therein, 10 and bending the portion 16' at right angle to the plane of the disk. The lugs 16' point toward disk 2; and the wheel 4, provided with spaced teeth 15, is positioned on the face of disk 1 which is adjacent plate 2. The disk 1 has its lugs 16' 15 arranged to move into successive contact with teeth 15, as shown in Fig. 4. The wheel 4 will be rotated each time a lug 16' is moved into contact with a tooth 15. Rotation of knob 6 will give a vernier adjustment of disk 1, producing 20 motion of the disk 1 between each pair of lugs 16' without shifting disk 2. If a large adjustment of shaft 13 is desired, this may be secured by rotating handle 7 which is directly secured thereto.

25 The disk 2 contains radially arranged apertures 18 alongside which the station names of transmitters having adjacent frequencies are marked. It will be understood that when the proper curve 10 is behind the aperture 18 and 30 also opposite the number corresponding to a desired station, such station will be tuned in and operate the receiver. In the operation of the device, to change the tuning from a station in group A to one in group B, the knob 7 is rotated until letter B thereon comes opposite the index line marked on panel 12 as shown in Fig. 1. Since disk 1 and condenser shaft 13 are connected to the knob, they rotate therewith whereby a rough adjustment of the condenser to some frequency within the B group of stations is secured.

40 As disk 1 rotates, one of its lugs 16' engages one of the teeth 15 of wheel 4 thereby rotating it and its attached gear 5c. This causes idler gear 5b to in turn rotate gear 5a and its attached disk 45 2 to such a position that the B group of station names comes into view in window 11. To select a particular station of this group, the operator rotates knob 6, which, through the engagement of friction wheel 5d with the rear surface of disk 1, causes rotation of this disk until the curve 10 thereon which appears in slot 18 in disk 2, is 50 directly opposite the desired station name. As clearly shown in Fig. 1, one of the curves 10 appears opposite station numbered 2 of group B indicating that the program from this station is 55 being received. It will further be understood

that while the curve on disk 1 is moving alongside the station names, the disk 2 is stationary since a lug 16' of disk 1 is out of engagement with the tooth 15 which it has just left. In other words the lugs 16' and teeth 15 provide an intermittent drive for disk 2 when the disk 1 is rotated by knob 7 through a rather large angle.

Having described my invention, what I claim and desire to secure by Letters Patent is:

1. Means for indicating the position of a tuning shaft, comprising the combination of a disk supported by said shaft, said disk having a plurality of groups of station names marked thereon, a second disk secured to said shaft and having a separate index thereon for each group of station names, gearing connections between said disks, and a control knob mechanically connected to said second disk.

2. Means for indicating the position of a tuning shaft, comprising the combination of a disk 20 mounted on said shaft, said disk having a plurality of apertures therein, a plurality of station indicia marked alongside each of said apertures, a rotatable member secured to said shaft behind said disk and having a plurality of indexes, each 25 of which is arranged to register with a different one of said apertures, gearing connecting said rotatable member and disk and manual control means for adjusting said rotatable member.

3. A tuning indicator comprising in combination, a panel, a window opening in said panel, a tuning shaft passing through said panel, a handle secured to said shaft in front of said panel, a disk mounted on said shaft at the rear of said panel and having a plurality of groups of station 35 indicia marked thereon, the station indicia of each separate group being arranged to lie behind said window opening, a second disk secured to said shaft at the rear of said panel and having a separate index adapted to cooperate with each 40 group of said station indicia, gearing connecting said disks, a second shaft passing through said panel and connected to said second disk and a control handle secured to said second shaft in front of said panel.

4. Means for indicating the position of a tuning device comprising a shaft secured to said device, a disk secured to said shaft and provided with a plurality of apertures formed in its periphery, a second disk loosely mounted on said 50 shaft and being marked with a plurality of radially arranged groups of station names, a wheel having a plurality of teeth adapted to successively enter said apertures and gearing connecting said wheel and second named disk.

ERWIN KÖNIG.
